D 11

John R. Remington, Lowndes County, Alabama
Letters Patent No. 11, dated Oct. 6th 1863

The schedule referred to in these Letters Patent and markings
part of the same. —

To all whom it may concern: Be it known that I,
John R. Remington of Lowndes County and State of Alabama,
have invented a new form or configuration of condensing worm
and apparatus for the purpose of smoking coffee and tea, and I do
hereby declare that the following is a full and exact description of
the same reference being had to the accompanying drawing, ma-
king part of this specification.

Fig. 1st is a vertical section of the coffee or tea pot, taken through
the center of spout and handle, in a line corresponding with the
line A or A of Fig. 2.

Fig. 2. is a horizontal projection or top view of the coffee or tea
pot, and shows the juxtaposition of its parts, the eye of the observer
being supposed directly over each, point. 16. is the spout.

D. is the handle, hollow, with the upper part made into a re-
cipient for cold water.

C. is a receptacle for cold water, through which the condensing
tube E. passes.

F. is the condensing tube, commencing in the spout and curv-
ing over the top of the coffee or tea pot, so as to form a convenient
handle, and entering the receptacle C, at or near the handle D, and
following the shape of the receptacle C, twice, more or less around
with sufficient descent to discharge the condensed vapor, enters the
handle D, and curving in the form of a worm, terminates in
the main body of the coffee or tea pot, above or beneath the surface
of the coffee or tea, in the coffee or tea pot.

This condensing tube F. is to be, or may be used for the pur-

2.

The shape or direction of the condensing tube is shown by dotted lines in Figs. 1 & 2.

In Figs 1 & 2, A, is the lid, for the introduction of the coffee or tea into the coffee or tea pot, and is made to close紧密 tight by means of cork or other elastic substances.

B, is a safety valve, placed over the end of the spout.

C, is a tube to draw off the water from within the receptacle whenever it may be desirable.

In fig. 2, D, is a lid through which the cold water is introduced into the receptacle E, if cold water be used.

What I claim as my invention, and desire to secure by letters patent for a design, is the form or configuration of the coffee or tea pot, as a whole: - that is, the coffee or tea pot together with its condensing apparatus as described.
